UNITED STATES PATENT OFFICE.

AUGUSTUS H. COSGROVE, OF UNION HILL, NEW JERSEY, ASSIGNOR TO SCOVILL MANUFACTURING COMPANY, OF WATERBURY, CONNECTICUT, A CORPORATION OF CONNECTICUT.

TACK-FEED-CONTROL MECHANISM FOR TACK-FASTENED BUTTON-ATTACHING MACHINES.

Application filed February 15, 1923. Serial No. 619,195.

To all whom it may concern:

Be it known that I, AUGUSTUS H. COSGROVE, a citizen of the United States, residing at Union Hill, in the county of Hudson and State of New Jersey, have invented a certain new and useful Improvement in Tack-Feed-Control Mechanism for Tack-Fastened Button-Attaching Machines, of which the following is a full, clear, and exact description.

This invention relates to a tack-feed control mechanism for tack-fastened-button attaching machines of the type shown and described in the copending joint application of Frank E. Warner and the undersigned Augustus H. Cosgrove, filed December 1, 1922, Serial No. 604,279.

The particular object of the present invention is to provide a tack cutoff mechanism for the tack raceway of such machines, and also a tack raceway clearing device for freeing the tack raceway of slugs, lint and foreign particles which would have a tendency to clog the raceway and interfere with the feed of tacks and hence the proper operation of the machine.

The invention consists in a tack-feed control mechanism for tack-fastened-button attaching machines comprising a tack raceway to which tacks may be fed from a suitable hopper, such as that illustrated and described in the application above mentioned, this raceway being provided with a tack cutoff mechanism adapted to operate upon the tack heads rather than upon their shanks, which latter is the more common practice. This cutoff is so connected with its operating mechanism as to provide a limited amount of lost motion to accommodate the movement of the operating mechanism should the cutoff by any chance become jammed in tack releasing position.

The invention consists further in a combination and arrangement of parts for opening the tack raceway at its discharge end for the purpose of freeing the raceway of slugs and the like, comprising a horizontally pivoted member adapted to be swung out of tack guiding relation to the tack raceway, and a tack detent associated with the tack raceway and actuated by movement of the movable member to prevent escape of tacks from the tack raceway when the mov-

able member is moved out of tack guiding relation thereto, as I will proceed now to explain and finally claim.

In the accompanying drawings illustrating the invention, in the several figures of which like parts are similarly designated, Figure 1 is a fragmentary sectional side elevation showing the mechanism embodying my invention and various parts of the machine operatively associated therewith. Fig. 2 is a plan view, on a larger scale, of the parts of the machine embodying my invention. Fig. 3 is an enlarged fragmentary sectional elevation looking at the opposite side of the machine from that illustrated in Fig. 1. Fig. 4 is a front elevation showing those parts of the machine illustrated in Fig. 2. Fig. 5 is a perspective view showing one side of the pivoted portion of the tack raceway, and the bearing screw and clutch spring for same, and Fig. 6 is a perspective view of the opposite side of the pivoted portion of the tack raceway. Fig. 7 is a perspective view, looking from above, of the base plate upon which the parts embodying the invention are mounted. Fig. 8 is a bottom perspective view of the locking lever for the pivoted member. Fig. 9 is a perspective view of the tack pusher.

Referring particularly to Fig. 1, 1 indicates the bed of the machine upon which is mounted a frame 2 upon which are arranged the various parts of the machine comprising my invention. 3 is a button raceway provided with a button cutoff 4 operated by a lever 5 through a roller 6 carried by said lever and in contact with a cam 7 mounted upon a cam shaft 8, the roller 6 being normally maintained in contact with the cam 7 by means of a spring 5'. All of these parts may be and are here shown as substantially the same and operate in the same manner as those shown and described in the application above mentioned.

9 is a tack raceway which extends preferably at an angle downwardly to a point adjacent to the center line of a setting anvil 10 and setting plunger 10', Fig. 3. A continuation or guideway at right angles to the raceway 9 is formed by means of a fixed guide member 11 and a movable member 12, the latter having a bearing at 13 upon a bearing screw 14. Adjacent to the bearing

13 the movable member is recessed as at 15 (see Figs. 3 and 5) to form a pocket for a clutch spring 16 which provides sufficient clutching or frictional effect to maintain 5 the movable member in raised or outswung position as shown in dotted lines in Fig. 4. The bearing screw 14 attaches the movable member 12 pivotally to a stand 17 which acts as a support for the lower end of the 10 raceway 9, and for the movable member 12 and the tack cutoff hereinafter referred to. This stand is attached to a base plate 18 (Fig. 7), which in turn is fastened by screws 19 and 20 to the frame 2. The movable 15 member 12 is held in raceway-forming or tack-guiding relation to the stationary guide member 11 by means of an undercut lug 21 which engages a similarly undercut portion or lip 22 of the base plate 18, whereby possible upward tilting of the movable member 20 vertically from the base plate is prevented, and by a locking lever 23 (see Fig. 8) pivoted at 24 to the base plate 18 and provided with a projection 25 adapted to enter a recess 26 in the side of the movable member. 25 This lever is made preferably of spring metal and is adapted to be held in locked position by means of a tapered detent 27 which engages with a recess 28 in the base 30 plate. The locking lever is provided with a handle 29 by which it may be moved into and out of locking position, and the base plate 18 is provided with a slabbed off or chamfered portion 30 upon which the detent 27 may ride to snap into the recess 28.

In order to facilitate moving of the movable member 12 a handle 30' is provided.

Obviously, the guide member 11 and movable member 12 form the sides or tracks of 40 the guideway, the bottom thereof being formed by the base plate 18.

It will be seen that by this arrangement when a tack becomes jammed in the lower portion of the raceway or a slug or foreign particle is encountered therein, the raceway may be cleared by swinging the locking lever to unlocked position, as shown in dotted lines in Fig. 4, and then, by grasping the handle 30', the movable member 12 45 of the raceway may be swung outwardly and upwardly about its pivot 14 to the position shown in dotted lines in Fig. 4, or as near thereto as is necessary to accomplish the desired purpose, thus completely removing one side or track of the guideway and moving it out of contact with the base plate 18 and out of such position as to form a possible obstruction to the fingers of the operator when removing slugs or the like, 50 and the member 12 will be frictionally retained in such position by spring 16. With the pivoted member 12 in this latter position, it is necessary to provide means to prevent all the tacks in the raceway 9 from 55 being discharged therefrom, and to this

end I provide a tack detent 31 pivoted at 32 to the raceway 9 and provided with a tack intercepting finger 32' and a rider 33. The rider 33 rests upon a cam 34 formed as a part of the movable member 12, and the 70 cam 34 so operates upon the rider that when the movable member 12 is in the position shown in full lines in Fig. 4, the finger 32' will be raised free of the path of the tacks in the raceway 9, but when the movable 75 member is in the position shown in dotted lines in Fig. 4, the finger 32' will drop to tack intercepting position with respect to the raceway 9, thus permitting free movement of tacks down the raceway when the 80 movable member 12 is in tack guiding position, and intercepting and preventing movement of the tacks in the raceway 9 when the movable member is swung out of tack guiding position.

In machines of this type, it is necessary to successively feed tacks singly from the tack raceway to the setting anvil and this is usually accomplished by means of a tack cutoff which lies flat upon the face of the raceway and has pivotal movement about an axis at right angles to the face of said raceway, this cutoff adapted to be oscillated to discharge tacks one at a time to a point where they are picked up and advanced to the setting anvil by means of a tack pusher. Cutoffs of this character operate upon the shanks of the tacks and, though it seldom occurs, are apt to tilt the tacks so as to cause jamming of the same in the raceway. I have provided the usual type of tack pusher 35 (see Fig. 9), but have devised a new form of tack cutoff 36, which is pivoted in the stand 17 upon a bearing screw 37 and oscillates upon its pivot in a plane 90 transverse to the discharge end of the tack raceway 9. This cutoff has a lip 38 (see Fig. 3) which is adapted to intercept the tacks as they drop against the face 39 of the movable member 12, by engagement with their heads rather than with their shanks, and this lip is connected with an arcuate slot 40 which allows the heads of the tacks to escape when the cutoff is moved to tack 95 releasing position. A stop portion 41 is provided which, when the cutoff is moved to tack releasing position, will cover and hence close the discharge end of the raceway 9 to prevent the discharge of tacks following the one being fed to the anvil. The tack cutoff is oscillated by means of a lever 42 clamped and keyed to a stud shaft 43 carried by and oscillated with the lever 5 and having a link 44 provided with a pin 45 which operates in a slot 46 in the tack cutoff. 100 The actuation of lever 42 to raise link 44 will move the cutoff to tack releasing position, and upon the reverse actuation of the lever 42 the cutoff will be returned to tack intercepting position by means of a spring 105 110 115 120 125 130

47 having one of its ends connected to an extension 48 on the cutoff and its other end fastened to a stationary part of the machine. It will thus be seen that when the lever 5 is actuated by the cam 7 to operate the button cutoff 4 to permit feed of a button to the setting mechanism, the tack cutoff will be simultaneously operated through the mechanism just described to permit the feed 10 of a tack to the setting mechanism.

As the tacks slide down the raceway and successively enter the slot 40 of the cutoff they will be correctly positioned with respect to the guideway formed by guide 11 15 and member 12 by striking against the upturned portion of member 12, which acts as an abutment.

As previously stated, slugs and foreign particles often get into the tack raceway, 20 and if such a slug or particle were to cause such jamming of the tack cutoff when once it was moved to tack releasing position that the spring 47 would not be strong enough to return it to tack discharge interrupting 25 position, damage to the mechanism would probably result if operation of the machine were continued. It is therefore advisable to provide some means for permitting return tack feeding movement of the lever 42 and 30 its link 44 and pin 45 without imparting this movement to the tack cutoff. The slot 46 is therefore provided, for it will be seen that if the tack cutoff has been moved to tack releasing position and becomes jammed in that 35 position, further reciprocation of the lever 42 and link 44 will merely cause the pin 45 to ride up and down in the slot 46.

I provide against injury to the machine due to possible jamming of either the tack 40 or button cutoff during the feeding operation of same, by the arrangement of the cam and lever mechanism 5, 6, 7, 42, 43 which allows the cam to continue in its rotation without operating the lever 5 for the 45 reason that when either cutoff is jammed the lever 5 will be held in such position that the roller 6 is out of contact with the cam 7 until its high portion advances.

The tack pusher 35 is operated by means 50 of a link 49 connected with a sliding frame 50 which carries a roller 51 bearing against a cam 52 mounted on the cam shaft 8, the frame 50 and with it the link 49 and pusher 35 being moved outwardly by the cam 52 and 55 inwardly by means of a pair of springs 53, these springs being connected at one end with an extension 54 of the frame 50 and at their other ends with a stationary part of the machine. These parts are the same as 60 shown and described in the application hereinabove referred to.

It will thus be seen that I provide a tack cutoff which is designed to be as near as possible non-jamming, and associate with this 65 cutoff means whereby the tack raceway may

be cleared in case a slug or other foreign particle is encountered or in case of jamming, thereby preventing, as nearly as is practicable, interruptions in the service of the machine, and making possible the easy 70 clearing of the machine and its prompt return to service in case it is temporarily disabled through jamming or fouling of the tack feed.

Although I have herein shown and de- 75 scribed a particular embodiment of my invention, I do not consider it as limited there- to except as hereinafter pointed out in the claims.

What I claim is:-

1. In a tack feed control mechanism for tack fastened button attaching machines, a base plate, a tack raceway extending at an angle thereto and having a discharge end, a stationary guide member associated therewith and with said base plate and forming a continuation of said raceway and a movable member complementary to said stationary guide and forming a guideway with said guide and said base plate, said 90 member being movable upon an axis at right angles to the face of said raceway and adapted to be moved out of tack guiding relation to the discharge end of said raceway and out of proximity to said base 95 plate, for the purpose specified.

2. In a tack feed control mechanism for tack fastened button attaching machines, a tack raceway having a discharge end, a stationary guide cooperating therewith and 100 forming an extension thereof, a movable member complementary to said guide and adapted to be held in tack guiding relation with respect thereto and movable out of such tack guiding relation, and a tack detent operatively associated with said raceway and adapted when said movable member is moved out of tack guiding relation to close said raceway against the escape of tacks therefrom but held normally out of such 110 raceway closing position.

3. In a tack feed control mechanism for tack fastened button attaching machines, a tack raceway having a discharge end, a movable guide member pivoted adjacent to the 115 discharge end of said raceway and provided with a cam surface, a tack detent pivoted on said raceway and having a finger adapted to interrupt the escape of tacks therefrom and a rider engaging said cam, said cam when 120 said movable member is in normal tack guiding position acting to maintain said finger out of tack feed interrupting position and when said movable member is moved out of tack guiding position allowing said finger 125 to fall into tack feed interrupting position.

4. In a tack feed control mechanism for tack fastened button attaching machines, a base plate, a tack raceway having a discharge end, a setting anvil spaced apart therefrom, 130

- 4
- and means associated with said base plate and forming therewith a guideway between said tack raceway and anvil and including a movable member located adjacent to the discharge end of said raceway and extending therefrom to said anvil when in normal position, said movable member adapted to be moved about an axis arranged at right angles to said raceway whereby it is shifted out of tack guiding relation with respect to said raceway and clear of said base plate to thereby interrupt its tack guiding function between said raceway and anvil and permit unobstructed access to said guideway.
- 15 5. In a tack feed control mechanism for tack fastened button attaching machines, a base plate, a tack raceway having a discharge end, a setting anvil, a pair of guides associated with said base plate and extending from the discharge end of said raceway to said anvil to form a guideway, one of said guides being pivoted upon an axis at right angles to said raceway and adjacent to the discharge end thereof and capable of being swung upon its pivot out of contact with said base plate and out of tack guiding relation with respect to said anvil, and means for locking said pivoted guide member in tack guiding relation.
- 30 6. In a tack feed control mechanism for tack fastened button attaching machines, a stand, a tack raceway having a discharge end supported by said stand, a stationary guide member located adjacent to and forming a continuation of said raceway, a movable member complementary to said stationary guide member and when in normal position forming with said guide member a tack guideway, a bearing member extending through said movable member and pivotally attaching the same to said stand, and a friction clutch interposed between said stand and said movable member whereby when said movable member is pivotally adjusted it will be maintained in adjusted position by said friction clutch member.
- 35 7. In a tack feed control mechanism for tack fastened button attaching machines, a frame, a base plate mounted thereon, a stand rising from said base plate, a tack raceway having a discharge end supported by said stand, a stationary guide member located adjacent to and forming a continuation of
- said raceway, a movable member complementary to said stationary guide member and when in normal position forming with said guide member a tack guideway, said movable member being pivoted upon said stand, and means for locking said movable member in normal tack guiding position with respect to said stationary guide including a lug on said movable member and a complementary lip on said base plate whereby vertical movement between said movable member and base plate is prevented, and a locking lever pivoted on said base plate and having an extension engaging the side of said movable member and a detent engaging said base plate whereby movement of said movable member about its pivot is prevented.
- 40 8. In a tack feed control mechanism for tack fastened button attaching machines, a tack raceway having a discharge end, a movable guide member arranged adjacent to the discharge end of the raceway and forming an abutment for the tacks descending the raceway, a tack cutoff arranged between said discharge end and abutment arranged for pivotal action transversely with respect to said discharge end and adapted to operate upon the tacks successively as they strike against said abutment, and means for imparting oscillation to said cutoff.
- 45 9. In a tack feed control mechanism for tack fastened button attaching machines, a tack raceway having a discharge end, a movable guide member arranged adjacent to the discharge end of the raceway and forming an abutment for the tacks descending the raceway, a tack cutoff arranged between said discharge end and abutment arranged for pivotal action transversely with respect to said discharge end and adapted to operate upon the tacks successively as they strike against said abutment, means including a link and lever connection for imparting oscillation to said cutoff, and a lost motion connection between said link and said cutoff whereby said link may be moved independently of said cutoff as specified.
- 50 100 In testimony whereof I have hereunto set my hand this 8th day of February, A. D. 1923.
- AUGUSTUS H. COSGROVE.
- Witness:
M. GUTH.
